W. Miller ATTORNEY

UNITED STATES PATENT OFFICE.

GEORGE NIXON, OF SANDYVILLE, OHIO.

STIRRUP.

SPECIFICATION forming part of Letters Patent No. 374,992, dated December 20, 1887.

Application filed June 13, 1887. Serial No. 241,106. (No model.)

To all whom it may concern:

Be it known that I, GEORGE NIXON, a citizen of the United States, and a resident of Sandyville, county of Tuscarawas, State of Ohio, have invented a new and useful Improvement in Saddle-Stirrups, of which the following is a full, clear, and exact description, reference being had to the accompanying drawings, making part of this specification.

10 My invention relates to an improvement in saddle-stirrups; and it consists in certain features of construction and combinations of parts, as will be hereinafter described, and pointed out in the claims.

15 Figure 1 is a side elevation of a saddle-stirrup representing my invention. Fig. 2 is same view of saddle-stirrup, showing an application of an additional or re-enforcing spring. Fig. 3 is same view of a saddle-stirrup, showing 20 my invention as applied between the stirrup and the saddle. Fig. 4 is a view in perspective of a stirrup having one side of the bow disengaged, showing one manner of construction.

25 Similar letters of reference illustrate corresponding parts in all of the figures of the accompanying drawings.

Letter A represents the bow of the stirrup, which may be made of any suitable material, 30 preferably of malleable iron or steel; C, the supporting or stirrup strap, which may be of any of the well-known and approved kinds, and B one form of spring.

As shown in Fig. 1, the lower end of the 35 bow A is bifurcated, the prongs a spread apart as far as may be desired to form a broad base or support for attachment to the spring B. On the ends of the prongs a there are provided tenons b, and on the apex of the bow a loop, 45 d, for the stirrup-strap. Said loop and bow may be integral, or the loop may have a pivotal or swivel connection with the bow.

The spring B may be made of thin plate-steel and of the form substantially as shown 45 in Fig. 4, having a body portion, h, provided with perforations k and a spring portion, l, which is narrower than the body portion and is turned back over the body, as shown in the

accompanying drawings. The tenons b are placed in the perforations k and riveted in the 50 usual way of forming such fastenings. The movement and elasticity of the spring may be regulated by the thickness of the spring-plate and the length and form of the spring. In using the U-shaped spring I prefer to enlarge 55 the closed end, as shown at m, as by such form I find the spring more elastic and less liable to break.

I do not wish to confine myself to this particular form of construction, as the U-shaped 60 spring as herein shown may be applied to many of the well-known forms of stirrup now in use by forming the spring as shown, except that the body portion h should be narrow enough to pass inside of the bow, in which position the spring may be riveted to the bottom 65 or cross-bar of the stirrup.

For the purpose of obtaining a stronger spring, or one adapted to support a heavy 70 burden, I prefer to introduce a coiled-wire 70 spring, D, as shown in Fig. 2, said spring to be made of such size of spring-wire as may produce the desired amount of resistance in the spring.

Another form of construction is that shown 75 in Fig. 3, in which a coil-spring, E, is placed between the stirrup and the stirrup-strap, or at any point between the stirrup and saddle. In this form my invention may be applied to any of the forms of stirrups and saddles now 80 in use, and by the use of either of the forms shown and described much of the hardship now endured by persons whose duties demand that much of their time be spent on horseback is obviated, and it also increases the pleasure 85 of those who ride on horseback for pleasure only.

Having thus fully described the nature and object of my invention, what I claim, and desire to secure by Letters Patent, is— 90

1. The combination, herein described, with a saddle-stirrup, of a U-shaped spring adapted to form the foot-support of the stirrup, substantially as set forth.

2. The combination, herein described, with 95 a saddle-stirrup, of a U-shaped spring form-

ing the foot-support of the stirrup and a coiled spring located between the arms of said **U**-shaped spring, substantially as set forth.

3. The combination, herein described, with 5 a saddle-stirrup, of a **U**-shaped spring forming the foot-support of the stirrup, said spring being provided at its closed end with an enlarged portion, *m*, and having its lower arm

wider than its upper arm, for the purpose substantially as set forth.

In testimony whereof I have hereunto set my hand this 10th day of June, A. D. 1887.

GEORGE NIXON.
